UNITED STATES PATENT OFFICE.

PHILIP A. BOWEN, OF LYNN, MASSACHUSETTS, ASSIGNOR TO LILLIAN A. LITTLE, OF LYNN, MASSACHUSETTS.

LAST.

1,115,279.

Specification of Letters Patent. Patented Oct. 27, 1914.

Application filed May 31, 1913. Serial No. 770,910.

To all whom it may concern:

Be it known that I, PHILIP A. BOWEN, a citizen of the United States, residing at Lynn, county of Essex, State of Massachusetts, have invented an Improvement in Lasts, of which the following description, in connection with the accompanying drawing, is a specification, like characters on the drawing representing like parts.

10 This invention relates to divided lasts and has for its object to provide a last of this type which can be used throughout all the successive operations required in the manufacture of shoes, thus obviating the necessity of changing the last in the shoe after the latter is partially finished.

In the manufacture of shoes it is now the common practice to use one type of last for the lasting operation and to remove 20 this last and substitute for it a so-called follower last which is used during some of the subsequent or finishing operations of the shoe. This necessitates two lasts for each shoe, and where the styles or shapes 25 of lasts are changed it necessitates the making of two lasts of every style and shape.

My improved last is made with a fore part and a heel part and with means for locking these two parts together so as to provide 30 a last of sufficient rigidity to be used in the lasting operation, said last having a novel construction by which the heel part can be moved relative to the fore part thereby to shorten the last when it is to be removed from or inserted into a shoe without stretching the latter.

A last embodying my invention is particularly useful in the manufacture of pumps and all types of low shoes because by means 40 of it the entire operation of manufacturing the pump and low shoes can be completed on one last and the last can be removed from the shoe without stretching the upper edge of the quarter.

45 The features wherein my invention resides will be more fully hereinafter described and then pointed out in the appended claim.

In the drawings I have shown a selected 50 embodiment of my invention which is illustrative of the principle thereof and which I will now proceed to describe.

Figure 1 is a side view of the last made 55 in accordance with the invention; Fig. 2 is a view partly in section showing

the last shortened for insertion into or removal from a shoe; Fig. 3 is a rear view of the fore part of the last.

My improved last is cut diagonally across the instep portion along the line 1 thereby 60 to constitute a fore part 2 and a heel part 3. The heel part is shown as having a metal heel plate 4 thereon, and is provided with a last-pin-receiving socket 5, all as usual. The heel part 3 is adapted to have a sliding movement on the fore part 2 along the line of division 1, thereby to shorten the last, as shown in dotted lines Fig. 2, and said fore part has also the capability of a swinging movement relative to the fore 70 part, as indicated in full lines Fig. 2.

To guide the two parts of the last in their sliding movement, I have herein shown the fore part of the last as provided with a guiding groove 6 in which is received a 75 rib 7 formed on the heel part of the last. This rib is herein shown as formed by making a groove 8 in the heel part of the last and then securing in said groove by glue or otherwise a cylindrical guiding member 80 7 of a size to fit the groove 6.

The two parts of the last are rigidly held in their operative position relative to each other by a clamping bolt 9 which is situated at right angles to the division line 1 and extends through an aperture 10 in the heel portion and into an aperture 11 in the fore portion, said bolt having screw-threaded engagement with the nut 12 which is anchored in the fore part. In the construction herein 90 shown the fore part of the last has an aperture 13 leading thereto from the bottom side through which the nut 12 can be inserted and positioned, said nut when in place having engagement with a shoulder 19. The nut is 95 held in place against said shoulder by a plug 14 which is inserted into the aperture 13 after the nut is positioned, and said nut is held from turning by wings or ribs 15 which extend laterally from the nut and are 100 embedded in the wood of the last.

The heel part of the last is cut away to provide a recess 16 to receive the head 17 of the clamping bolt, said recess having a seat 18 against which the head of the clamping bolt fits. Since the clamping bolt extends at right angles to the division line 1, it follows that when the bolt is tightened the two parts of the last are very firmly clamped together. The shoulder 19 prevents the nut 110

from giving and the clamping bolt operates to clamp the two parts of the last so firmly together that the last will be sufficiently rigid for use in the lasting and other similar operations of the shoe.

In order to remove the last from the shoe, the clamping bolt 9 is first removed, and then the operator slides the heel part of the last upwardly along the division line 1, as 10 shown in dotted lines Fig. 2, this operation shortening the last because of the inclination of the division line. After the heel part has been moved into the dotted line position, then it can be swung upwardly into the full 15 line position Fig. 2 to clear it from the top of the counter and the last may then be withdrawn from the shoe.

I will preferably provide a connecting member which permanently connects the two 20 parts of the last, but yet which allows this sliding and swinging operation. The advantage of such a connecting member is that all danger of the parts of the last becoming separated and one or the other part becoming lost is avoided. The connecting device 25 herein shown is in the form of two links 20 which are received in recesses 21 and 22 in the fore and heel parts of the last, respectively. Said links are provided with slots 30 23, 24, preferably curved as shown, through which extend pins 25 and 26 carried by the two parts of the last, this pin-and-slot connection allowing both the sliding and swinging movement of the heel part of the last 35 above referred to. These links prevent the

heel part from being separated from the fore part and thus insure that the two parts of the last will always be together whenever they are to be used.

Having fully described my invention, 40 what I claim as new and desire to secure by Letters Patent is:

A last divided diagonally across the instep portion thereof to present a heel part and a fore part, one of the meeting faces of said 45 parts having a guiding groove extending from one end to the other thereof, and the other having a guiding rib fitting said groove, means to clamp said two parts rigidly together, said two parts having alined 50 recesses in their meeting faces, connecting members loosely occupying said recesses, each connecting member having a slot at each end, and pins extending transversely through said parts and the recesses therein 55 and through the slots in said connecting members, said connecting members being pivotally mounted on the slots and permitting both a sliding and a pivotal movement between the parts of the last while at the 60 same time permanently connecting them together.

In testimony whereof, I have signed my name to this specification, in the presence of two subscribing witnesses.

PHILIP A. BOWEN.
